(57) **CLAIM**

The ornamental design for a casing for electronic cigarette capsules, as shown and described.

DESCRIPTION

FIG. 1 is a top view of a casing for electronic cigarette capsules, shown with the lid removed for clarity of disclosure; FIG. 2 is a first side elevational view thereof;

FIG. 3 is a second side elevational view thereof;

FIG. 4 is a perspective view thereof;

FIG. 5 is a first side elevational view of the casing for electronic cigarette capsules, shown with the lid on, for clarity of disclosure;

FIG. 6 is a second side elevational view thereof; and,

FIG. 7 is a perspective view thereof.
